VOLUMETRIC FEEDER FOR FIBROUS MATERIALS

Arthur L. Mottet, Longview, Wash., assignor to The Long-Bell Lumber Company, Longview, Wash., a corporation of Missouri

Application June 15, 1953, Serial No. 361,793

4 Claims. (Cl. 19—96)

This invention relates to a volumetric feeder for fibrous materials, and particularly pertains to apparatus for continuously delivering fibrous material such as defibered wood at a predetermined constant volumetric rate to collecting or conveying means where it is ready for further processing.

In certain applications it is desirable to provide a feeder for fibrous material which will feed the material volumetrically at a uniform continuous rate for subsequent processing operations. For example, in the manufacture of pressed fiberboard by the dry process, wood first is reduced to fibrous form. The resulting fibrous product then is passed continuously through apparatus for coating it with resin, for forming it into felts or mats, and for pressing it into fiberboard of the selected density. In order to operate the process satisfactorily and in order to obtain mats and fiberboards of uniform density it is necessary that the fiber be fed into the various processing units at a constant rate of volume.

This obviously is a result that is difficult of accomplishment. In the first place, the rate of fiber production usually is not constant. In the second place, the character of the fibers is such that they tend to clump together and form floes, which makes it difficult to feed them uniformly. Further, the fibers tend to hang up, or to jam, and plug the units of metering apparatus through which they may be passed. Still further, it is difficult to control and vary the rate of fiber feed within carefully determined limits because of the foregoing factors and because of the very low density of the fiber material which is handled.

I now have discovered that the foregoing and other difficulties inherent in volumetric fiber feeding may be overcome through the use of apparatus described in the accompanying specification and claims, considered together with the drawings, wherein:

Figure 1 is a plan view, partly in section, of the presently described volumetric feeder for fibrous material; and

Figure 2 is a view in side elevation of the apparatus of Figure 1, partly broken away, better to illustrate the interior construction.

As is illustrated in the drawings, the presently described volumetric feeder comprises a housing 10 the top of which communicates with feed chute or hopper 12. The discharge opening in chute 12 has a width or thickness a , the significance of which is to be discussed below; a depth substantially codimensional with the corresponding dimension of the apparatus; and an indeterminant height which may, however, be quite substantial. In this way a storage space is afforded to build up a reservoir of fibrous material, thereby compensating for fluctuations in fiber feed, such as may occur, for example, during the defibering of wood blocks.

Chute 12 tapers outwardly and downwardly and extends within housing 10 to such an extent that its discharge end is immediately adjacent a pair of feed rolls 14, 16. These are stationed side by side immediately

2

below the chute for receiving the material discharged thereby in the area between the rolls.

The rolls are provided with spikes 18, 20 for engaging the fibrous material and for carrying it into the area between the rolls. The spacing of the spikes is such as to engage the fibrous material without becoming clogged thereby, and also such as to provide a clearance distance between the spikes as the rolls rotate.

Feed roll 14 is rotatably mounted on a shaft 22 journaled in bearings 24, 26. Feed roll 16 is rotatably mounted on a shaft 28 journaled in bearings 30, 32. Bearings 24, 26 are mounted on a frame member provided with slots 27, and bearings 30, 32 are similarly mounted with slots 33 so that the position of the two feed rolls relative to each other may be varied as desired.

It is to be noted that in order to have a uniform feed of fibrous material, such as wood fibers, between rolls 14 and 16, one or more of several critical factors must be observed. In the first place, the diameter b of the rolls 15 should be substantial as compared with the corresponding parallel width or thickness a of the chute opening. Thus, diameter b should be at least equal to, preferably from two to four times thickness a . In the second place, 20 the sidewalls of chute 12 should extend as closely as possible to the surfaces of rolls 14, 16. Thus the opposed surfaces of the two rolls become restricted continuations of the side walls of the chute.

Also, and of particular importance, the distance c separating the opposed surfaces of the two feed rolls 30 should be substantially less than the corresponding parallel width or thickness a of the chute opening. Thus, 35 c should be between $\frac{1}{4}$ and $\frac{3}{4} a$, preferably about one-half a . This insures that the loose, fluffy mass of fibers present in the chute will be compacted to a coherent 40 mat which can be passed at a uniform rate between the rolls. Under these conditions it will be apparent that the column of fiber within chute 12 will move in the direction of the feed rolls uniformly at substantially the same rate as the compressed column moves between the rolls.

Drive means are provided for driving feed rolls 14, 16 in the feed direction synchronously with each other at the desired rate. In the illustrated form the drive 45 comprises a worm gear 34 keyed to shaft 22 and a worm gear 36 keyed to shaft 28. These two gears are driven respectively by worms 38, 40 splined to a common shaft 42. Shaft 42 in turn is journaled in bearings 44, 46. It carries on one of its ends the pulley 48 connected through belt 50 to pulley 52 on the variable speed motor 50 54. In this manner roll 14 may be driven clockwise and roll 16 counterclockwise, as viewed in Figure 2, synchronously but very slowly, for example, at a speed of but 1 or 2 revolutions per minute.

Fibers transmitted between rolls 14, 16 are in a coherent compressed condition as has been indicated above. Accordingly, in this condition they are amenable to combing for dislodging individual fibers which may then be dispersed and collected for subsequent processing. In the 55 illustrated form, the combing means employed comprises a combing roll 56. It is provided with a plurality of teeth 58 which are dimensioned and spaced to clear teeth 18, 20 on the feed rolls. The teeth of the combing roll project well within the fiber compression area so that they act upon the compressed fibers, disentangling them and combing out individual fibers, thereby avoiding the dropping away of fibrous clumps from the apparatus.

The combing roll assembly includes a shaft 60 which is journaled in bearings 62, 64. It is driven through pulley 66, interconnected through belt 68 to pulley 70 on motor 72. This motor is of variable speed but drives the comb roll at a relatively high rate, for example, 400

revolutions per minute as compared with the slow rate of revolution of the feed rolls.

Suitable collecting apparatus is employed for receiving the individual fibrous elements combed out of the compressed mass by comb roll 56. Although this may assume various forms, it may conveniently comprise a conveying belt 74.

Thus by the present invention there is provided a relatively simple apparatus for feeding fibrous materials such as wood fibers in a continuous, uniform stream substantially free from clumps and flocs. The apparatus is so designed as to be free from difficulties due to jamming, plugging and hanging up which plague the operator of the conventional fiber feeder. Also, it is readily adjustable to accommodate fibrous materials of varying characteristics and to feed them at a selected feed rate.

It is to be understood that the form of my invention herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. A volumetric feeder for fibrous materials comprising a vertical chute for containing and transmitting a quantity of material, the bottom end of the chute having an outfeed opening of uniform width and depth, a pair of parallel, rotatably mounted, spiked feed rolls stationed side by side below and in close proximity to the outfeed opening of the chute with their axes parallel to the sides of the opening forming its depth for receiving between them material discharged by the chute, the feed rolls having their opposed peripheral surfaces separated by a distance of about one-half the corresponding parallel width of the chute opening and having a diameter which is from two to four times the said corresponding parallel width of the chute opening, adjusting means for adjusting the spacing between the feed rolls, motor means connected to the feed rolls for driving them in the feed direction, the chute being proportioned to feed the material at a rate at least equal to the peripheral speed of the feed rolls, the latter thereby engaging the material and compressing it between the rolls to about one-half its original bulk density while advancing it toward the discharge side of the feed rolls, a comb roll rotatably mounted below the feed rolls and operable between the same in the region of fibrous material compression, motor means for driving the comb roll at a rate substantially greater than the feed rolls and sufficient to comb out from the compressed mass of fibrous material substantially individual fibrous elements, and collecting means stationed adjacent the comb roll for collecting the fibrous elements separated thereby.

2. A volumetric feeder for fibrous materials comprising a chute for containing and transmitting a quantity of fibrous material, the bottom end of the chute having an outfeed opening of uniform width and depth, a pair of rotatably mounted, parallel, feed rolls stationed side by side below and in close proximity to the outfeed opening of the chute with their axes parallel to the sides of the opening forming its depth for receiving between them material discharged by the chute, the feed rolls having their opposed peripheral surfaces separated by a distance which is between $\frac{1}{4}$ and $\frac{3}{4}$ the corresponding parallel width of the chute opening and having diameters at least equal to the said corresponding parallel width of the chute opening, motor means connected to the feed rolls

for driving them in the feed direction, the chute being proportioned to feed the material at a rate at least equal to the peripheral speed of the feed rolls, the latter thereby engaging the material and compressing it while advancing it toward the discharge side of the feed rolls, a comb roll rotatably mounted between the feed rolls at the discharge side thereof and operable in the region of compression of the fibrous material, and motor means for driving the comb roll at a rate substantially greater than the feed rolls and sufficient to comb out substantially individual fibrous elements from the compressed mass of fibrous material.

3. A volumetric feeder for fibrous materials comprising a chute for containing and transmitting a quantity of fibrous material, the bottom end of the chute having an outfeed opening of uniform width and depth, a pair of rotatably mounted, parallel, feed rolls stationed side by side below and in close proximity to the outfeed opening of the chute with their axes parallel to the sides of the opening forming its depth for receiving between them material discharged by the chute, the feed rolls having their opposed peripheral surfaces separated by a distance which is between $\frac{1}{4}$ and $\frac{3}{4}$ the corresponding parallel width of the chute opening and having diameters at least equal to the said corresponding parallel width of the chute opening, motor means connected to the feed rolls for driving them in the feed direction, thereby engaging the material and compressing it while advancing it toward the discharge side of the feed rolls, a comb roll rotatably mounted between the feed rolls at the discharge side thereof and operable in the region of compression of the fibrous material, and motor means for driving the comb roll at a rate substantially greater than the feed rolls and sufficient to comb out substantially individual fibrous elements from the compressed mass of fibrous material.

4. A volumetric feeder for fibrous materials comprising a chute for containing and transmitting a quantity of fibrous material, the bottom end of the chute having an outfeed opening of uniform width and depth, a pair of parallel rotatably mounted feed rolls stationed side by side below and in close proximity to the outfeed opening of the chute with their axes parallel to the sides of the opening forming its depth for receiving between them material discharged by the chute, the feed rolls having their opposed peripheral surfaces separated by a distance less than the corresponding parallel width of the chute opening and having diameters at least equal to the said corresponding parallel width of the chute opening, motor means connected to the feed rolls for driving them in the feed direction, thereby engaging the material discharged by the chute and compressing it while advancing it toward the discharge side of the feed rolls, a comb roll rotatably mounted between the feed rolls at the discharge side thereof and operable in the region of compression of the fibrous material, and motor means for driving the comb roll at a rate substantially greater than the feed rolls and sufficient to comb out substantially individual fibrous elements from the compressed mass of fibrous material.
